UNITED STATES PATENT OFFICE

ALFRED WILLIAM BENNIS, OF BOLTON, ENGLAND

FURNACE GRATE

Application filed January 8, 1930, Serial No. 419,349, and in Great Britain March 9, 1929.

The present invention relates to furnace grates and more particularly to grates of the travelling chain type.

In travelling chain grates, due to the variation in conditions under which the grate must work, it is often necessary to take up and let out slack in the chains and links or grate bars forming the endless travelling chain grate, and complicated mechanism has been necessary in order to accomplish this.

The object of the present invention is to devise a simple means for doing this.

In many cases at the present time, the catenary of the lower traverse or run of a travelling chain grate engages at its lowest point with a stationary skid bar, and this skid bar is used in travelling chain grates both in the horizontal type and in that type in which the upper run or traverse of the grate is inclined to the horizontal.

According to the present invention the skid bar is displaced to distort the catenary of the lower run or traverse of the grate and to take up a proportion of the load on the upper run or traverse of the grate caused by the catenary of the lower traverse or run, thus slackening the chains and links or bars forming the endless run of the grate.

A number of skid bars each extending longitudinally of the grate may be provided at spaced intervals across the grate or further, a single support may be provided in the form of a skid plate, this plate extending longitudinally of the grate and across the whole or the major portion of the width of the grate.

The skid bar or plate which may either be horizontally disposed or inclined to the horizontal, may be vertically displaced so that its face is adapted to take up any one of a number of positions in parallel planes, or further, the skid bar may be pivoted at or near one end and its other end adapted to be displaced about said pivot.

Again, each skid bar or the skid plate may be substantially triangular in section with its hypotenuse engaging with the catenary of the lower traverse of the grate. Each skid bar or the skid plate may be mounted on rollers whereby it may be displaced lon-

gitudinally of the grate to act substantially in the form of a wedge, displacement longitudinally of the grate in one direction, raising the lower run or traverse of the chains and links or grate bars, while longitudinal displacement in the other direction allows the lower run or traverse of the grate to approach the catenary position.

Means are provided for retaining each skid bar or the skid plate in any displaced position.

The invention is more particularly described with reference to the accompanying diagrammatical drawings, in which:—

Figure 1 diagrammatically shows, in side elevation, a travelling chain grate with the lower catenary supported on one form of skid bar.

Figure 2 diagrammatically illustrates a modified form of construction of skid bar.

Figure 3 diagrammatically shows a further modified form of skid bar.

Figure 4 diagrammatically shows a still further modified form of skid bar.

In the construction according to Figure 1 of the drawings, the travelling chain grate consists of an upper run 10 and a lower run 11. The lower run is supported on skid bars 12 which are mounted on a frame 13. The frame 13 is supported on wheels 14 through bearing brackets 15, said wheels being adapted to be displaced along horizontal rails 16.

It will be seen from a study of Figure 1 that the skid bars 12 being inclined and the rails 16 being horizontal, the whole frame 13 forms, in effect, a wedge. For the purpose of displacing the frame together with the skid bar from the position shown in full lines to the position shown in chain dotted lines, thereby to allow the lower catenary of the grate to assume a more natural position and to take up slack in the upper run of the grate, a worm wheel 17 mounted on a shaft 18 having a squared or other manipulative end 19 drives a worm wheel 20 to which is attached through a shaft 21 a drum 22 around which a wire rope 23 is wound.

This wire rope extends from the drum 22 beneath the skid bar to the rear end of this and passes around a fixed idler pulley 24 and

thence back again for connection at its other end at 25 to the skid bar.

On winding the drum 22 in the direction to tighten the rope the skid bars are drawn to the right of Figure 1 thus lifting the lower run of the chain, whilst on loosening the wire rope by unwinding the drum the skid bar frame 13 automatically moves to the left in Figure 1 to take up a position as indicated in chain dotted lines, i. e., until the rope again becomes tight when further movement of the skid bar is prevented.

In the modified form of construction illustrated in Figure 2 the skid bars which are illustrated at 26 are horizontally disposed irrespective of their position of adjustment. In this case, the skid bars are mounted on screw jacks 27 at both the front and rear of the grate, these screw jacks being interconnected by a tie bar 28, whilst a further tie bar 29 is provided between one screw jack and a fixed part of the grate structure shown as a part of the ashpit wall. The usual gear illustrated diagrammatically at 30 is supplied for adjusting the height of the movable support 31 of the screw jacks.

In the construction illustrated in Figure 3 a skid bar 32 is mounted about a pivot 33 at the rear end of the grate whilst its front end is mounted upon a displaceable member 34 of a screw jack 35. The skid bar in its lowest position of adjustment is illustrated in this drawing in chain dotted lines.

In the construction according to Figure 4 a horizontal skid bar 36 is mounted on a frame 37 for displacement with wheels 38 along inclined rails 39 carried by the bed B of the ashpit. In order to effect this displacement the front of the frame 37 is connected to a rigid rod or the like draw means 40 passing through a stationary part of the furnace 41, displacement of the draw means 40 being effected by a screw and nut or a jack as diagrammatically illustrated at 42.

It will be obvious that numerous other modified forms of construction of adjustable or displaceable skid bars may readily be devised without departing from the scope of the invention.

I declare that what I claim is:

1. A furnace grate comprising a traveling endless chain including an upper run which forms the fuel supporting surface of the grate and a lower run depending therefrom, a skid bar for supporting a portion of the weight of the lower run of the chain, and means whereby the skid bar may be moved toward or from the upper run.

2. A furnace grate comprising a traveling endless chain including an upper run which forms the fuel supporting surface of the grate and a lower run depending therefrom, means located beneath the lower run for supporting a portion of the weight of the lower run of the grate, and means for adjusting the po-

sition of said supporting means whereby a greater or lesser portion of the weight of the lower run is supported thereby.

3. A furnace grate comprising a traveling endless chain including an upper run which forms the fuel supporting surface of the grate and a lower run depending therefrom, means for driving said chain, means for supporting a portion of the lower run in its travel, and devices for varying the vertical position of said supporting means whereby to support a greater or lesser part of said lower run.

4. A furnace grate comprising a traveling endless chain including an upper run which forms the fuel supporting surface of the grate and a lower run depending therefrom, means for driving said chain, at least one displaceable skid bar for supporting a portion of the weight of the lower run, and means to hold said skid bar in any one of a number of positions relative to said upper run whereby to vary the portion of the weight of said lower run supported by said skid bar.

5. A furnace grate comprising a traveling endless chain including an upper run which forms the fuel supporting surface of the grate and a lower run, means located intermediate the ends of said runs for supporting a portion of the weight of the lower run of the chain, and devices for varying the vertical position of said supporting means.

6. A furnace grate comprising a traveling endless chain including an upper run which forms the fuel supporting surface of the grate and a lower run depending therefrom, at least one skid bar for supporting the lower run of the grate and means for adjusting said skid bar to support a variable portion of the weight of said lower run whereby to vary the pull exerted by said lower run upon said upper run.

7. A furnace grate comprising a traveling endless chain including an upper run which forms the fuel supporting surface of the grate and a lower run depending therefrom, at least one skid bar positioned to engage with the lower run and to support a portion of the said lower run, and means operable to vary the position of said skid bar relatively to said upper run to distort said lower run to a variable extent to take up a predetermined proportion of the load on the upper run caused by the weight of said lower run.

8. A furnace grate comprising a traveling endless chain including an upper run which forms the fuel supporting surface of the grate, and a lower run depending therefrom, and means for adjustably distorting the lower run of the grate whereby to vary the tensile pull thereof upon the upper run.

9. A furnace grate comprising a traveling endless chain including an upper run which forms the fuel supporting surface of the grate, and a lower run depending therefrom;

a plurality of skid bars at predetermined spaced intervals across and beneath said grate for supporting a portion of the weight of the lower run of said chain and means for displacing said skid bars relative to said upper run and for retaining them in their position of adjustment.

10. A furnace grate comprising a traveling endless chain including an upper run which forms the fuel supporting surface of the grate, and a lower run depending therefrom, a plurality of skid bars at spaced intervals across and beneath the grate for supporting a portion of the weight of the lower run of said chain, a bed for the support of said skid bars inclined relatively to the supporting surface of said skid bars, and means for adjusting said skid bars along said bed and for retaining them in their adjusted position.

20. 11. A furnace grate comprising a traveling endless chain including an upper run which forms the fuel supporting surface of the grate and a lower run depending therefrom, a member having a wedge shape in a vertical plane parallel to the direction of travel of the chain for supporting a portion of said lower run, fixed means for providing a support for the bottom surface of said wedge-shaped member and extending at an angle to the upper run of the chain, and means for displacing the member parallel to the direction of movement of said chain whereby to support a greater or lesser portion of the lower run of the chain.

35. 12. A traveling chain grate comprising an endless chain including a horizontal upper run which forms the fuel supporting surface of the grate, and a lower run depending from each end of the upper run, at least one skid bar having a horizontal upper surface for supporting said lower run, rollers on which said skid bar is mounted, an inclined bed for the support of said rollers and screw means for adjusting said rollers and skid bar along said bed and for retaining them in their adjusted position.

In witness whereof, I have hereunto signed my name this 18 day of December, 1929.

ALFRED WILLIAM BENNIS.
